UNITED STATES PATENT OFFICE.

WALTER REENSTROM, OF CHICAGO, ILLINOIS.

SMOKE-JACK.

1,108,234.

Specification of Letters Patent. Patented Aug. 25, 1914.

Application filed May 7, 1914. Serial No. 836,943.

To all whom it may concern:

Be it known that I, WALTER REENSTROM, a citizen of the United States, and a resident of the city of Chicago, county of Cook, and State of Illinois, have invented certain new and useful Improvements in Smoke-Jacks, of which the following is a specification.

My invention relates to smoke jacks and has for its object the production of a device 10 of this character adapted to effectually serve in the capacity of a safety device to prevent heating of the structure through which the smoke pipe passes, and which will serve the additional function of a ventilator.

15 A further object is the production of a device as mentioned which will be of durable and economical construction and which will be efficient in use.

Other objects will appear hereinafter.

20 With these objects in view my invention consists in the combinations and arrangements of parts hereinafter described and claimed.

The invention will be best understood by 25 reference to the accompanying drawing forming a part of this specification, and in which—

Figure 1 is a central vertical section of a smoke jack embodying my invention, the 30 same being shown installed in operative position, and Fig. 2 is an enlarged section taken on line $x-x$ of Fig. 1.

The preferred form of construction as 35 illustrated in the drawing comprises a tubular member or drum 1 which projects through the ceiling 2 and roof 3 of the building in which the jack is installed. Provided at the upper exteriorly projecting end of the member 1 is a hood 4. Said hood is 40 supported in operative position by arms 5 formed integral with the upper end of the member 1, the upper ends of said arms being secured to said hood by means of rivets 6.

The arms 5 result through the formation of 45 spaced recesses 7 in the upper edge of the member 1, said recesses, after the mounting of the hood 4 upon the member 1, constituting ventilation openings as will be readily understood. The lower edge of the hood 4 50 projects below the recesses or ventilation openings 7 so as to prevent the direct passage of air currents thereto, the hood 4 serving as a deflector to break up the currents before entering the member 1. Of course the hood 4 serves the additional func-

tion of a deflector for rain, preventing the entrance of the latter into the upper end of the member 1.

Arranged centrally in the member 1 is the smoke pipe 8, said smoke pipe being of less diameter than the member 1, so as to result in the formation of an annular air passage 9 intermediate the same and the member 1. This annular passage 9 serves the double function of an air passage for ventilation purposes and also as an insulating jacket to prevent heating of the structure through which the smoke pipe passes. The smoke pipe is secured in central position in the member 1 by means of rings 10 which embrace said pipe, said rings being rigidly secured in position by arms 11 projecting inwardly from the member 1 as clearly shown in Fig. 2.

The upper end of the hood 4 is provided 75 with an opening of a diameter such as to snugly receive the upper end of the smoke pipe 8. Arising from said end of said hood is a tubular extension 12 at the upper end of which is provided a conical hood 13. Said 80 hood 13 is positioned in registration with the upper edge of extension 12, being provided with a depending flange 14 at the central opening therein which snugly embraces the upper end of said extension. The lower 85 edge of said flange is supported upon an annular bead 15 provided at the upper end of said extension, said flange being securely held in position between said bead and an outwardly projecting flange 16 provided at 90 the upper end of extension 12 which engages over the upper side of the hood 13 as shown. Spaced above the hood 13 is a cap 17 of a diameter the same as that of said hood, said 95 cap being securely held in operative position by means of arms 18 formed integral and upwardly projecting from the upper edge of member 12, said cap being riveted to the upper ends of said arms.

A smoke jack of the construction set forth 100 will be found highly efficient as a safety device and ventilator and at the same time the production of the hood 13 and cap 17 at the upper end of extension 12 will result in improving and accelerating the draft in the 105 smoke pipe. The integral construction of the arms 5 and 18 results in a strong and durable arrangement as well as one which is economical and less expensive than a construction employing separate supporting 110

arms for this purpose which are secured as by riveting at their lower ends to the pipe or tubular member from which they arise.

While I have illustrated and described the 5 preferred form of construction for carrying my invention into effect, this is capable of variation and modification without departing from the spirit of the invention. I, therefore, do not wish to be limited to the precise 10 details of construction set forth, but desire to avail myself of such variations and modifications as come within the scope of the appended claims.

Having described my invention what I 15 claim as new and desire to secure by Letters Patent is:

1. A device of the class described comprising a tubular member; a smoke pipe of less diameter than said tubular member extending through the latter; means for centering said smoke pipe in said tubular member; a conical hood at the upper end of said tubular member, there being openings at the upper end of said tubular member below said hood; and a tubular extension at the upper end of said tubular member of less diameter than the latter in which the upper end of said smoke pipe snugly fits, substantially as described.

2. A device of the class described comprising a tubular member; a smoke pipe of less diameter than said tubular member extending through the latter; means for centering said smoke pipe in said tubular member, said means comprising a ring embracing said smoke pipe; and arms having their outer ends rigidly secured to said tubular member and having their inner ends connected with said ring for rigidly supporting the latter, substantially as described.

3. A device of the class described comprising a tubular member; a smoke pipe of less diameter than said tubular member extending through the latter; means for centering said smoke pipe in said tubular mem-

ber, said means comprising means embracing said smoke pipe; arms inwardly projecting from said tubular member for supporting said embracing means; and a conical hood at the upper end of said tubular member, there being openings at the upper end of said tubular member below said hood, substantially as described.

4. A device of the class described comprising a tubular member; a conical hood arranged at the upper end of said tubular member; and arms formed integral with and upwardly projecting from said end of said tubular member for supporting said hood, there being ventilation openings formed between said arms at the under side of said hood, substantially as described.

5. A device of the class described comprising a tubular member; a conical hood arranged at the upper end of said member; the upper end of said member being recessed to form supporting arms for said hood and to constitute ventilation openings between said arms at the under side of said hood, substantially as described.

6. A device of the class described comprising a tubular member; a conical hood arranged at the upper end of said tubular member, said hood having a central opening at its upper end; an annular flange provided at said opening embracing said tubular member; a bead on said tubular member with which the lower end of said flange engages; and an outwardly turned flange at the upper end of said tubular member engaging over the upper side of said hood around the opening therein, substantially as described.

In testimony whereof I have signed my name to this specification in the presence of 85 two subscribing witnesses.

WALTER REENSTROM.
